L. C. DOANE

FLOOR LAMP

Filed June 17, 1925.

UNITED STATES PATENT OFFICE.

LEROY C. DOANE, OF MERIDEN, CONNECTICUT, ASSIGNOR TO THE MILLER COMPANY, OF MERIDEN, CONNECTICUT, A CORPORATION OF CONNECTICUT.

FLOOR LAMP.

Application filed June 17, 1925. Serial No. 37,656.

The present invention relates to floor lamps and is more particularly directed toward a type of floor lamp in which the lamp bulb and shade may be upwardly directed as in a torchière, or in which the lamp and shade may be downwardly directed as in a bridge lamp.

An object of the present invention is to provide a convertible lamp of the above type in which the lamp bulb, the socket and the shade are supported on a frame pivoted to one side of the lamp standard so that they may be bodily moved to direct the shade upwardly or downwardly, as desired.

A further object of the invention is to provide an improved assemblage of lamp socket and shade by which these parts may be mounted and assembled as a unit; and in which the shade may be readily removed.

Other and further objects will appear as the description proceeds.

The accompanying drawings show for purposes of illustrating the invention one of the many possible embodiments in which the present invention may take form, it being understood that the drawings are merely illustrative of the invention, rather than limiting the same.

In these drawings:

Fig. 1 is an elevational view, with parts in section, showing in full lines the position the parts assume when the lamp is used as a torchière, and showing in dotted lines the position the parts assume when the lamp is used as a bridge lamp;

Fig. 2 is an enlarged fragmentary sectional view taken on the line 2—2 of Fig. 3; and

Fig. 3 is a fragmentary detailed view showing parts in section and taken on the line 3—3 of Fig. 2.

The upright standard of a floor lamp is indicated at 10 which may be in the form of a length of hollow tubing. A U-shaped member 11 is suitably attached to the upper end of this standard. As shown in the drawings, the left side 12 of this U-shaped member is offset to provide a seat for a purpose to be described, while the opposite side 13 is slotted and drilled to receive a hinge member 14 and a pintle 15.

The lamp socket 16 is carried by a suitable frame work which is adapted to be at-

tached to the hinge member 14 and extend across to the opposite side of the U-shaped upper end of the lamp standard. As here shown, this frame work includes a sheet metal stamping 17, to the center of which the lamp socket is attached and securely fastened by a nut 18, and a reenforcing ring 19 which is mounted in the periphery of the disk shaped stamping. This stamping may be round or polygonal, as desired, and screws 20 may be passed through the ring, the periphery of the stamping and into the hinge member 14 so as to securely attach the stamping to the hinge member. The reenforcing ring may be attached in place by soldering or by screws, as desired.

The ring 19 is preferably somewhat narrower than the outer wall of the stamping so as to provide a shoulder 21 against which the lower portion 22 of a shade frame 23 may rest. A convenient way of removably fastening this shade frame in place is to provide the shade frame with arms 24 which are attached to a ring 25 carried underneath a threaded ring 26 which is adapted to cooperate with the threads 27 on the ordinary lamp socket. By removing the threaded ring one is able to remove the shade, the arms 24 and the ring 25.

Where the lamp socket 16 is of the pull chain type, the chain may be passed through the guide tube 28 in the side wall of the stamping. The lamp cord may be brought up through the hollow standard 10 and carried alongside the other leg of the U, as indicated at 29, and then passed through the hole 30 therein. The cord is then carried upwardly so as to extend through the upper face of the side 13 of the U-shaped member. It is then passed through a hole 31 in the stamping 17.

When one desires to convert the lamp from the torchiere, indicated in full lines, to the bridge lamp, illustrated in dotted lines, it is only necessary to loosen the wing nut 32 and swing the parts carried by the hinged member 14 in an obvious manner. In doing this, the pull chain and cord readily accommodate themselves to the new position. One can, of course, if desired, tighten the wing nut so as to hold the lamp in any desired angular position. As shown in the draw-

ings, the extreme upper end of the left hand side of the standard is ornamented in the same manner as the hinge member 14 so as to carry out the balancing of the lamp design when the parts are in the full line position. This hinge member may be shaped, as indicated, so that it acts as a stop when the lamp is lowered to the dotted line position.

10 It is obvious that the invention may be embodied in many forms and constructions and I wish it to be understood that the particular form shown and described is but one of the many forms. Various modifications 15 and changes being possible, I do not in any way limit myself with respect thereto.

I claim:

1. A floor lamp having an upright standard, a shade supporting and lamp carrying 20 frame, and a horizontal pivotal connection between the stand and frame and placed to one side of the axis of the standard, the frame being movable through 180° to convert the lamp from a bridge lamp to a 25 torchière.

2. A floor lamp having a U-shaped upper end, a frame pivotally attached to one side of the U, and adapted to rest on the other side of the U, a shade extending upwardly from the frame, and a lamp carried by the frame within the shade, the frame, lamp and shade being bodily movable about the pivot so that the shade and lamp extend downwardly.

3. A floor lamp having a U-shaped upper end, a frame pivotally attached to one side of the U, and adapted to rest on the other side, an upwardly extending lamp socket 30 permanently attached to the frame, and a shade supported by the frame and lamp socket, the frame and attached parts being bodily movable to invert the lamp socket and shade.

4. A floor lamp having an upright standard, a frame pivoted at one side of the top 45 of the standard to swing through 180° about a horizontal axis, a lamp socket and shade bodily carried by the frame, and stops so placed that the axis of the lamp socket is 50 vertical in either extreme position.

5. In a floor lamp, in combination, a disk shaped stamping, a reenforcing ring carried inside the periphery of the stamping, a lamp socket attached to the center of the 55 stamping, a shade frame adapted to fit the reenforcing ring, a clamping ring threaded on the outside of the lamp socket, and connections between the shade frame and clamping ring for holding the frame 60 against the reenforcing ring.

6. In a floor lamp, in combination, a disk shaped stamping, a reenforcing ring carried inside the periphery of the stamping, a lamp socket attached to the center of the 65 stamping, a shade frame adapted to fit the

reenforcing ring, a clamping ring threaded on the outside of the lamp socket, connections between the shade frame and clamping ring for holding the frame against the reenforcing ring, a hinge one side of which is 70 attached to the stamping, and a lamp stand to which the other side of the hinge is attached.

7. A lamp having an upright support, provided with a U-shaped upper end, a hinge having a horizontal axis and carried at one side of the U, a stamping attached to one side of the hinge and resting on the opposite side of the U, a lamp socket attached to the center of the stamping and extending 80 upwardly, an upwardly extending shade having a frame fitting inside the stamping, and means cooperable with threads on the lamp socket for clamping the frame in place, the parts carried by the hinge being 85 bodily movable so that the lamp and shade may extend downwardly.

8. A lamp having an upright support, provided with a U-shaped upper end, a hinge having a horizontal axis and carried at one side of the U, a stamping attached to one side of the hinge and resting on the opposite side of the U, a lamp socket attached to the center of the stamping and extending upwardly, a reenforcing ring carried inside the stamping, an upwardly extending shade having a frame fitting inside the stamping, and means cooperable with threads on the lamp socket for clamping the frame in place, the parts carried by the hinge being bodily movable so that the lamp and shade may extend downwardly.

9. A lamp having an upright support, provided with a U-shaped upper end, a hinge having a horizontal axis and carried at one side of the U, a stamping attached to one side of the hinge and resting on the opposite side of the U, a lamp socket and switch attached to the center of the stamping and extending upwardly, a reenforcing ring carried inside the stamping, an upwardly extending shade having a frame fitting inside the stamping, the switch being covered by the shade and stamping so as to be inaccessible, a pull chain for operating the switch, the chain passing outwardly through the stamping, and means cooperable with threads on the lamp socket for clamping the frame in place, the parts carried by the hinge being bodily movable so 120 that the lamp and shade may extend downwardly.

10. A lamp having an upright support, provided with a U-shaped upper end, a hinge having a horizontal axis and carried at one side of the U, a stamping attached to one side of the hinge and resting on the opposite side of the U, a lamp socket attached to the center of the stamping and extending upwardly, a reenforcing ring 130

carried inside the stamping, an upwardly extending shade having a frame fitting inside the stamping, inwardly directed spokes carried by the frame, a ring attached to the inner ends of the spokes and extending around the socket, and a threaded sleeve threaded onto the lamp socket and engaging the latter mentioned ring to clamp the

frame in place, the parts carried by the hinge being bodily movable so that the lamp and shade may extend downwardly. 16

Signed at Meriden, in the county of New Haven and State of Connecticut, this 15th day of June, 1925.

LERoy C. DOANE.
